UNITED STATES PATENT OFFICE.

SIDNEY C. WALLACE, OF CHICAGO, ILLINOIS.

HOSE-SUPPORTER.

1,215,444.

Specification of Letters Patent. Patented Feb. 13, 1917.

Application filed March 22, 1916. Serial No. 85,980.

To all whom it may concern:

Be it known that I, SIDNEY C. WALLACE, a citizen of the United States, residing at Chicago, in the county of Cook, State of Illinois, have invented a new and useful Hose-Supporter; and I do hereby declare the following to be a full, clear, and exact description of the invention, such as will enable others skilled in the art to which it appertains to make and use the same.

This invention relates to the art of garment supporters, and more particularly to that kind for supporting hose.

One of the objects of the invention is to provide an improved hose supporter having simple, efficient and practical features of construction, for instance, improved means at the lower part of the fastener to receive a puckered part of the hose.

In practical fields the details of construction may necessitate alterations, falling within the scope of what is claimed.

The invention comprises further features and combination of parts, as hereinafter set forth, shown in the drawings and claimed.

In the drawings:

Figure 1 is a view in perspective showing the hose supporter as applied to a portion of a leg supporting the hose.

Fig. 2 is a view in front elevation of the fastener between the strand and the hose.

Fig. 3 is an edge view.

Fig. 4 is a sectional view on line 4—4 of Fig. 3.

Fig. 5 is a sectional view on line 5—5 of Fig. 2.

Referring more especially to the drawings, 1 and 2 designate two pieces of wire material, one end of the piece 1 is bent to form a plurality of eyes or coils 3 consecutively in alinement, and one end portion of a braided fabric strand is passed zig-zag through the coils 3, as shown in edge view in Fig. 3, the extreme portion of said end, after passing through the lowermost coil 3 is returned to the intermediate coil or eye 3, and inserted therethrough, thereby insuring the connection of the strand to said eyes. Below the coils 3 the piece of wire material 1 is bent to form a straight portion 4 of a length substantially as shown in Fig. 2. Beyond the straight portion 4, the wire material 1 is bent at 5 and 6, and then formed in a downwardly curved part 7 terminating in a spring coil 8, beyond

which the yieldable arm 9 is provided, which is bent at 10 and 11, thereby conforming to the shape of the part 7. The arm 9 beyond the bend 11 terminates in a straight portion 12, which when fastened in the hook 13 of the metal band 14, is parallel with the straight part 4. The arm 9 and the part 7 form the two sides of the loop of a hose supporting fastening device, which loop is designed to receive a pucker 15 of the hose 16^a, as shown in Fig. 1, thereby holding the hose in position. The other piece of wire material 2 is bent to form a loop, and the opposite end portions of the wire material 2 beyond the loop thereof are arranged in parallelism. The part 16 of the parallel portions of the wire material 2 extends upwardly beyond the other parallel part 17, and is formed into a plurality of eyes or coils 18, to receive the other end of the braided fabric strand 19, thereby holding the strand about the leg of the wearer, a trifle above the calf of the leg. The loop of the wire material 2 is bent in several places as shown, to provide two laterally extending side loops 20 and the central loop connecting bridge 21, which extends through the elongated loop of a wire material 1. Where the parallel parts 16 and 17 of the wire material 1 extend into the loops 20, said parts are curved as shown at 22, which engage the part 7 and the arm 9 as shown at 23. Referring to Fig. 3 it is to be noted that the loops 20 overlie the part 7 and the arm 9, and the portions 20^a of said loops 20 extend at acute angles to the part 7 and the arm 9, so that the portions 20^b of the loops 20 will engage the part 7 and the arm 9. It is to be noted that the band 14 extends about the straight portion 4 and the two parallel parts 16 and 17, and is provided with a tongue, to form a hook 13, which receives the portion 12 of the arm 9. When attaching a hose to the fastener, a pucker 15 is passed through the loop of the wire material 1, so that the loops 20 will extend into the pucker, so that where the loops 20 are designed to engage the part 7 and the arm 9, the puckered part of the hose is held frictionally in place, that is, when the portion 12 of the arm 9 is fastened to the hook 13, thereby securely supporting the hose. Said parallel portions 16 and 17 in Fig. 3 are out of alinement with the part 7 and the arm 9.

The invention having been set forth, what is claimed as new and useful is:

1. A hose supporter, comprising two clamping members provided with garter attaching means at their upper ends, means for clamping said members together, one of said members comprising an elongated loop, the other constructed from a single length of wire bent to provide a pair of adjacent parallel parts, which extend downwardly centrally of the loop member and then extend inwardly, and gradually curve outwardly, said outwardly extending portions of said parts diverging laterally, overlying the sides of said elongated loop, and terminating in side loops, the upper portions of said side loops extending inwardly toward and engaging the sides of the elongated loop, and said side loops connected by a bridge.
2. A hose supporter, comprising two clamping members, one constructed of a single length of wire bent to form a tapering loop provided at its lower end with a

spring coiled eye, said loop having a short free spring portion and an upwardly extending elongated part having garter attaching means at its upper end, the other clamping member having parts in parallelism with said elongated part, one of said parallel parts of the second member having garter attaching means at its upper end, said second clamping member having side clamping loops at its lower end to overlie and engage the sides of the tapering loop, a sleeve clamp surrounding and binding said parallel parts of both members together, and provided with a lateral hook to be engaged by the extremity of said short free spring portion.

In testimony whereof I have signed my name to this specification in the presence of two subscribing witnesses.

SIDNEY C. WALLACE.
